US0D1091324S

(12) United States Design Patent (10) Patent No.: US D1,091,324 S
(45) Date of Patent: * Sep. 2, 2025

(54) BOTTLE

(71) Applicant: Constance Lewis, Minneapolis, MN (US)

(72) Inventor: Constance Lewis, Minneapolis, MN (US)

() Term: 15 Years

(21) Appl. No.: 29/764,548

(22) Filed: Dec. 30, 2020

(51) LOC (15) Cl. 09-01

(52) U.S. Cl.

USPC D9/621; D9/520

(58) Field of Classification Search

USPC D9/600, 499, 520, 544, 601, 614, 621, D9/622, 624, 627, 516, 620, 530, 540, D9/564, 571, 575; D3/202, 270, D3/271.1–271.3; D7/301–303, 509–511, D7/514–517, 519, 520, 594, 595, 599, D7/604, 613, 619.2, 623, 628; D11/44, D11/48, 49, 53, 81–83, 157, 160, 131, D11/133, 136, 149, 150; D20/31, 32; D21/621, 623, 627, 649

Primary Examiner — Darcey E Gottschalk

(57) CLAIM

The ornamental design for a bottle, as shown and described.

DESCRIPTION

FIG. 1 is an elevation view of the front of the bottle; FIG. 2 is an elevation view of the back of the bottle; FIG. 3 is an elevation view of a first side of the bottle; FIG. 4 is an elevation view of a second side of the bottle; FIG. 5 is a top plan view of the bottle; FIG. 6 is a bottom plan view of the bottle; FIG. 7 is a first front perspective view of the bottle; FIG. 8 is a second front perspective view of the bottle; and, FIG. 9 is a back perspective view of the bottle. In the drawings, the broken lines depict portions of a bottle that form no part of the claim.

1 Claim, 9 Drawing Sheets
